ICE BLOCK UPENDING MACHINE

Peter H. Muller, Hillside Township,
Union County, N. J.

Application September 21, 1944, Serial No. 555,185

5 Claims. (Cl. 214—1)

1

Ice blocks are usually handled in ice manufacturing plants by sliding or conveying the blocks on their narrow longitudinal edges or faces, but for storage purposes the blocks are up-ended or turned so as to stand on end and thereby occupy less floor space.

Machines have been provided for up-ending blocks to permit handling of the blocks with a minimum of labor and to reduce the possibility of injury to the workers engaged in handling the ice. However, such machines are relatively complicated and expensive and do not handle the ice blocks as rapidly as desired.

Therefore, one object of my invention is to provide a machine for up-ending ice blocks which shall be simple and inexpensive in construction and operation and shall be capable of handling ice blocks rapidly and with a minimum of effort by the attendant.

Another object is to provide a machine of this character which shall include a tiltable or pivoted table or platform to receive an ice block "on edge," i. e., lying on one narrow longitudinal edge, and novel and improved mechanism for moving said table from horizontal to vertical position to turn the ice block upon one end.

Other objects are to provide novel and improved means for controlling operation of said table whereby said tilting mechanism shall be automatically started by movement of an ice block onto the table to swing the table upwardly and up-end and discharge the ice block, and the table shall automatically return to its normal horizontal position after the block has been discharged from the table; and to obtain other advantages and results that will be brought out by the following description in conjunction with the accompanying drawings in which.

Figure 1 is a side elevational view of an ice block up-ending machine embodying my invention showing the table partially elevated and a block of ice thereon illustrated by dot-and-dash lines.

Figure 2 is a front elevational view of the machine.

Figure 3 is a top plan view of the machine with portions broken away for clearness of illustration.

Figure 4 is a vertical longitudinal sectional view showing the table completely elevated.

Figure 5 is a fragmentary top plan view showing the table in its normal position and illustrating a cake of ice thereon by dot-and-dash lines, and

Figure 6 is a wiring diagram of the motor and switches for controlling operation of the table.

Specifically describing the illustrated embodiment of the invention, with the reference character 1 designates the floor or runway of an ice storage room in which my up-ending machine is installed. A table 2 to receive the ice blocks is

2

pivotedly mounted adjacent one end as indicated at 3 on bearing brackets 4 which are fastened to an I beam 5 mounted in the top edge of one wall 6 of a pit or opening which is disposed below the runway or floor 1. The table has a bottom wall 7 and is so mounted that when said wall is in horizontal position it is substantially flush with the upper surface of the floor 1 as shown by broken lines in Figure 4. The table also has side walls 8 and an end wall 9 which are of such size and so related to the bottom wall 7 and to each other as to receive a commercial ice cake or block 10.

The table 2 is thus mounted to swing vertically about the horizontal axis of the pivot 3 through an arc of substantially 90°, and a block of ice may be slid onto the table from the floor when the table is in its normal horizontal position. For tilting or elevating the table I have shown a mechanism including a crank shaft 11 journalled horizontally in bearings 12 and 13 in the pit, upon one end of which is a crank arm 14 pivotally connected at 15 to one end of a link 16, the other end of which is pivotally connected at 17 to the under side of the bottom wall 7 of the table, the parts being dimensioned and related so that the table will be elevated from its normal horizontal position to its vertical position during about one-half or 180° of the revolution of said crank and the table will return to its normal position by gravitational action.

The crank arm 14 is preferably power-driven from an electric motor 18 whose shaft 19 is connected with a speed-reducing mechanism 20 to a pinion 21 which in turn meshes with a gear 22 on the crank shaft 11.

It is desirable that the motor 18 be automatically controlled, and for this purpose I have shown a normally open electric switch 23 for starting the motor, mounted on a stationary support, e. g., the top of the pit wall, to be actuated by a plunger 24 mounted in the end wall 9 of the table and normally held by a spring 25 in spaced relation to the operating rod 26 of the switch 23 when the table is in its horizontal position as shown by broken lines in Figure 4. Also I have provided a normally closed limit switch 27 for stopping the motor when the table is in its elevated position, said switch being mounted on a stationary frame 28 at the pivoted end of the table and having an operating arm 29 normally influenced by a spring 30 to close the switch and to be engaged by a lug 31 on the table 2 when the table reaches its substantially vertical position at the end of the elevating operation as shown in Figure 4.

In order to permit starting and stopping of the motor under manual control, especially in emergencies, I also provide a normally open manually operable starting switch 32 and a nor-

mally closed manually operable stopping switch 33. These various switches are connected by a circuit with the motor and a known type of magnetic switch 34 so that when the switch 23 or the switch 32 is closed, the electric magnetic switch 34 will be operated to start the motor and to continue operation thereof until the lug 31 opens the switch 27 or the manually operated stop switch 33 is opened.

In operation of the machine, assuming that the table is in its normal horizontal position, an ice block 10 is slid from the floor 1 onto the table and into engagement with the plunger 24 so as to close the switch 23. Thereupon the motor 18 will be started and the crank arm 14 and link 15 will push the table upwardly as shown in Figure 1. The outer end of the ice block will engage a shoulder or ledge 35 on the floor adjacent the pivoted end of the table so as to prevent the block from sliding off the table until the latter has been fully elevated. Upward movement of the table will continue through an arc of approximately 90° until the table reaches its substantially vertical position shown in Figure 4, whereupon the ice block will tilt by action of gravity off the table onto the floor 1 where it may be received by an attendant and pushed to its desired position in the storage room. When the table 2 reaches its uppermost position the switch arm 29 is actuated by the lug 31 to open the switch 27 and stop the motor. At this time, the crank arm will be in approximately the position shown in Figure 4, and gravitational action on the table will cause the latter to swing downwardly and to rotate the crank arm 14 until the table reaches its normal position. If desired, downward movement of the table may be limited by a projecting flange 36 on the top wall of the pit. The table is then in position to receive another ice block, whereupon the operation may be repeated.

It will be seen that my machine is simple and inexpensive in construction and operation and that ice blocks may be rapidly handled thereby. It has been found that the machine will up-end 8 blocks of ice per minute, allowing adequate time for the blocks to be slid onto the table and to be pulled away from it after they have been up-ended. There are no complicated parts to get out of order and the operation of the machine is substantially automatic. Of course, if it is desired to stop the elevation of the table at any point, the manually operated stop switch 33 may be actuated, and should it be desired to start the motor to either elevate or lower the table, the manually operated starting switch 32 may be actuated. In this connection we might emphasize that it is possible to utilize the motor for lowering the table if desired, by operating the switch 32 at the proper time.

If desired, the crank arm 14 could be mounted on the low speed or out-put shaft 37 of the speed reducing gear 20 so as to eliminate the gear 22 and shaft 11, and this is preferable where an electric motor and speed-reducing gear combination is available which will give the required low speed for elevating the table.

While I have shown and described my invention as embodied in certain details of construction, it will be understood that this is primarily for the purpose of illustrating the principles of the invention and that many modifications and changes may be made in the construction of the

machine within the spirit and scope of the invention.

What I claim is:

1. In an ice up-ending machine, the combination with a horizontal runway for ice cakes having an opening therein, of a table to lie normally horizontally in said opening in approximately a common plane with said runway to receive ice cakes from the latter, said table being pivoted near one end thereof to swing in a vertical plane, a crank beneath said table to rotate in a plane parallel with the plane of movement of said table, a link pivotally connected at opposite ends to said crank and said table, said crank, said link and said table being so related that the table is swung upwardly from its horizontal position through an arc of about 90 degrees during 180 degrees revolution of said crank, and driving means below said runway and said table for rotating said crank.
2. The ice up-ending machine as defined in claim 1 with the addition of a shoulder adjacent said pivoted end of said table to be abutted by an ice cake on said table as the table is raised and over which said ice cake is tilted from said table onto said supporting surface.
3. The ice up-ending machine as defined in claim 1 wherein said driving means includes an electric motor, a switch in the motor circuit and carried on a stationary support and so constructed and arranged that it is closed by an ice cake when said cake is located on said table for up-ending, and a limit switch in said motor circuit constructed and arranged to stop the motor after the ice cake has been up-ended.
4. The ice up-ending machine as defined in claim 1 wherein said driving means includes an electric motor, a switch in the motor circuit and carried on a stationary support and so constructed and arranged that it is closed by an ice cake when said cake is located on said table for up-ending, and a limit switch in said motor circuit constructed and arranged to stop the motor after the ice cake has been up-ended, and wherein the relationship of said crank, said link and said table is such that the table will return to normal horizontal position by gravitational action after the motor is stopped.
5. The ice up-ending machine as defined in claim 1 wherein said driving means includes an electric motor, a limit switch in the motor circuit mounted on a stationary support, means on said table to be actuated by an ice cake when the latter is located on said table for up-ending so as to close said switch, a second limit switch in said motor circuit mounted on a stationary support and constructed and arranged to stop the motor after the ice cake has been up-ended.
